UNITED STATES PATENT OFFICE.

JOHN O'FALLON CLARK, OF CHICAGO HEIGHTS, ILLINOIS, ASSIGNOR TO AMERICAN MANGANESE STEEL COMPANY, OF CHICAGO, ILLINOIS, A CORPORATION OF MAINE.

DIPPER.

Application filed January 5, 1923. Serial No. 610,769.

To all whom it may concern:

Be it known that I, JOHN O'FALLON CLARK, a citizen of the United States, residing at Chicago Heights, in the county of Cook and State of Illinois, have invented certain new and useful Improvements in Dippers, of which the following is a specification.

This invention relates to dippers for excavating, dredging, digging and similar work and its object is to strengthen the connection of the bail bracket with the body of the dipper to avoid the strains and stresses to which the bracket is subjected in actual 15 operation.

The bail of the dipper is attached to the dipper body on each side thereof by a pin which passes through the bail bracket, the bail and the side of the dipper body. When 20 the dipper is lowered for scooping into the material to be dug the bail makes an angle of approximately 45° with the top or open part of the dipper, and when the dipper is pulled into the material the bail straightens 25 up perpendicularly to the top of the dipper and may, when the dipper is at its highest point, lean towards the front of the dipper fifteen or twenty degrees. In a complete digging operation the bail moves through an 30 angle of approximately sixty or sixty-five degrees. This angular pull of the bail on the body of the dipper causes a corresponding side pull on the bail brackets and likewise a shearing stress on the rivets that hold 35 the bail brackets to the dipper body.

It is my object to strengthen and reinforce the connection between the bail brackets and the dipper body by providing means other than the rivets for taking the side strain and 40 for holding the bail brackets in their proper position so that a more efficient connection between the bail brackets and the dipper body is provided.

In the accompanying drawings I have 45 illustrated a selected embodiment of the invention and referring thereto.

Fig. 1 is a side elevation of a dipper embodying the invention;

Fig. 2 is a detail view of a portion of a 50 dipper body and a bracket illustrating one embodiment of the invention;

Fig. 3 is a similar view illustrating another embodiment of the invention;

Fig. 4 is also a similar view illustrating 55 another embodiment of the invention and

showing the key and the rib or ledge detached.

Referring to the drawings, 5 is a dipper body, 6 the bail, 7 the bail bracket and 8 the pin which passes through the bail bracket, 60 the bail and the side of the body to attach the bail to the body. The bracket is attached to the side of the body by rivets 9 in the usual manner and the bracket is off set and provided with a shoulder 10 which engages 65 a rib or ledge 11 on the side of the dipper body. This ledge may be an integral part of the dipper body as shown in Fig. 2; or it may be an integral part of the bracket as 12 to engage a recess 13 in the side of the dipper body, as shown in Fig. 3; or it may be a 70 separate piece 14 to fit in a recess 15 in the side of the dipper body to be engaged by the shoulder 16 of the bail bracket as shown in Fig. 4.

In addition to the rivets I also provide a key 17 which may be an integral part of the side of the dipper body to engage a recess 18 in the bail bracket, as shown in Fig. 2; or it may be an integral part 19 of the bail 80 bracket to engage a recess 20 in the side of the dipper body, as shown in Fig. 3; or it may be a separate part 21 to engage a recess 22 in the side of the dipper body and a recess 23 in the bail bracket, as shown in Fig. 4. 85

The rib or ledge 11 relieves the rivets of the direct pull of the bail upon the dipper body and the key relieves the rivets of the side strains and stresses which would otherwise have a tendency to shear and loosen the 90 rivets. The key holds the bail bracket in its proper position and in conjunction with the rib or ledge prevents any movement of the bail bracket relative to the dipper body thereby confining the function of the rivets 95 practically to securing the bail bracket to the body since the key will prevent side strains and the rib or ledge will take the direct strains of the bail which would otherwise wear and have a tendency to loosen and 100 shear the rivets.

My invention is simple in character but it is of great value and importance in connection with dippers since they are subjected to unusual, irregular and tremendous strains 105 and stresses which require that all joints and connections be made with exceptional strength and rigidity; and this is especially true of the connection of the bail with the dipper body because if one connection is 110

broken the entire machine is rendered inoperative. My invention provides a strong and substantial connection which will relieve the rivets of much wear and most of the strains and stresses to which they have been subjected heretofore.

It is possible to vary the construction and arrangement of the parts to accomplish much the same results without departing 10 from my invention or sacrificing the advantages thereof and I reserve the right to make all such changes as fairly fall within the scope of the following claims:

I claim:

- 15 1. The combination of a dipper body, a bail bracket fastened thereto, and a key forming an interlocking connection between the body and the bracket.
- 20 2. The combination of a dipper body, a bail bracket fastened thereto, and a longitudinal key extending in the direction of the length of the bail bracket and forming an interlocking connection between the dipper body and the bracket.
- 25 3. The combination of a dipper body, a bail bracket, means for fastening the bracket to the body, and means interposed between

the bracket and the body to prevent shearing strains on the fastening means.

4. The combination of a dipper body, a 30 bracket fastened to the body, a transverse rib or ledge to prevent forward movement of the bracket in the direction of the pull on the bail, and a key angularly disposed with relation to said transverse rib or ledge to 35 prevent lateral movement of the bracket relative to the body.

5. The combination of a dipper body, a key rigid with the body, a bail bracket having a recess to engage said key, and means 40 for fastening the bracket to the body.

6. The combination of a dipper body having a transverse rib or ledge, a key integral with the body, a bail bracket having a shoulder to engage said rib or ledge and a 45 recess to engage said key, and means for fastening the bracket to the body.

7. The combination of a dipper body, a bail bracket fastened to the body, means to resist the strain of direct pull of the bail 50 upon the bracket, and means to resist strain of angular pull of the bail relative to the bracket.

JOHN O'FALLON CLARK.
